United States Patent Office.

JAMES LAMB, OF HUBBARDSTOWN, MASSACHUSETTS.

Letters Patent No. 74,920, dated February 25, 1868.

IMPROVED ROCKING-CHAIR.

The Schedule referred to in these Letters Patent and making part of the same.

TO ALL PERSONS TO WHOM THESE PRESENTS MAY COME:

Be it known that I, JAMES LAMB, of Hubbardstown, in the county of Worcester, and State of Massachusetts, have made a new and useful invention having reference to Chairs; and I do hereby declare the same to be fully described in the following specification, and represented in the accompanying drawings, of which—

Figure 1 is a side elevation,

Figure 2 a front view, and

Figure 3 a vertical section of a chair made in accordance with my invention.

The invention is an improvement in supporting the seat on the base of the chair, so that the seat, by a person while sitting upon it, may be vibrated or tilted back and forth as well as laterally with a pleasant motion.

The base-portion A of the chair is separate from the rest of the chair, and consists of a frame to rest directly upon a floor. I usually construct it of two cheeks or foot-bars, *a a*, and two connection-bars *b b*, and I extend from the middle of one to that of the other of such bars *b b* a bar spring-supporter, *c*. On this supporter I elevate and fasten two zigzag springs *B B*, formed as represented in figs. 2 and 3. Their upper levers I affix to a bar or cleat, *d*, fastened to the lower side of the chair-seat *C*. There project downward from the seat four short legs, *e e e e*, which rest on and are fastened to two side springs *D D*, arranged directly over the cheeks or foot-bars *a a*. Each spring, *D*, at its middle, is hinged to the upper part of a staple, *E*, extended up from the cheek or foot-bar, the whole being as represented in figs. 1 and 2. The arrangement of the zigzag springs, with reference to the staples, should be as shown in the said figures. The chair, while tilting on the staples, will be supported both by the zigzag springs and the side springs, the latter allowing it also to tilt or tip more or less laterally. Thus, the chair is not confined to a tilting motion in one plane only, but, by my arrangement and combination of springs, may be tilted in various directions. Furthermore, the zigzag springs are peculiarly favorable for the vibratory movements of the chair-seat, and are very much better than helical or spiral springs for such use.

I claim the arrangement as well as the combination of the middle or zigzag and the side or leaf-springs with the chair-seat and base, substantially as described, the whole being to operate as explained.
